METHOD FOR THE N-ALKYLATION OF
PHENYLAMINOACETIC ACID ESTERS

Norbert Brock, Brackwede, Engelbert Kühns, Gadderbaum, and Martin Schmeisser, Munich, Germany, assigns to Asta-Werke Aktiengesellschaft, Chemische Fabrik, Brackwede, Westphalia, Germany

No Drawing. Application January 23, 1951,
Serial No. 207,446

Claims priority, application Austria
January 25, 1950

4 Claims. (Cl. 260—471)

1
It is well known that compounds having aromatically bonded amino groups can be converted into the corresponding N-alkyl compounds by the action of dialkylaminoalkylchlorides. This reaction is generally carried out using the dialkylaminoalkylchloride in the form of a free base in the presence of neutral solvents. There is no information regarding the yield produced by this reaction.

As far as we are aware N-alkylations of phenylaminoacetic acid esters have not been carried out. Attempts to obtain the N-alkylation of phenylamino-acetic acid esters by the above-mentioned usual method, that is, by using the free base in the presence of neutral solvents have given very poor yields, in general not more than 20%.

On the other hand it has been discovered that surprisingly high yields of N-alkylation products are obtained in the N-alkylation of phenylamino-acetic acid esters, provided that the reaction is carried out in the absence of solvents with the aid of the hydrochloride of the dialkylaminoalkylchloride base. Under these conditions yields of 80% or more are obtained. It has been found that particularly good results are obtained if phenylaminoacetic acid iso-amylester is reacted, for example, with diethylaminoethylchloride hydrochloride in the absence of solvents. In this manner on the one hand, particularly high yields (over 80%) are obtained, while on the other hand, compounds are obtained which exhibit extremely valuable therapeutical properties.

Examples

50 g. of phenylamino-acetic acid iso-amylester is placed in a three tube round flask. 14 g. of diethylaminoethylchloride - hydrochloride are added agitating all the time, and a further 44 g. of the hydrochloride is added in three equal portions at an oil bath temperature of 120° C. The reaction mixture is maintained at this temperature for about 5 hours. After cooling, a reaction product is obtained comprising a viscous, brown-

ish translucent mass which may be treated as follows:

The reaction product is dissolved in water, made alkaline and then ether is added. After drying the etheric solution with sodium sulphate, the ether is removed and the residue is fractionally distilled in vacuo. After slight fore-runnings, the ester distils over at B. P. 165° to 180°. Yield 58 g.=80.11%.

The compound obtained by the N-alkylation of phenylaminoacetic acid iso-amyl ester is characterised in the form of its hydrochloride by excellent cramp-relieving action. It is in particular suitable for the treatment of spasms due to muscular or neural causes.

Since the hydrochloride of dialkylaminoethyl chloride, unlike the free base, is quite stable, it can be stored without any trouble and can be used the free base where the base used must be prepared from the hydrochloride with a considerable loss, and the base on account of its sensitivity and instability must be specially prepared from the hydrochloride for each operation.

Occasionally N-alkylations of compounds containing aromatically bonded amino radicals and not belonging to the series of the phenylamino-acetic acid esters have also been carried out by using, instead of the free dialkylaminochloride base, the corresponding hydrochloride and by treating without solvents. There is however no data at hand to show that better yields are obtained than by the usual process using the free base. Therefore no conclusions could be drawn that in the N-alkylation of phenylamino acetic acid esters using the hydrochloride in the absence of solvents, yields could be obtained which are a multiple of, for example, four times the yield which is obtained by using the free base in the presence of solvents. It could not be foreseen either, that compounds according to the invention would be obtained with high yields, for example 80% or more, having special therapeutic properties in particular cramp-relieving actions as for example those exhibited by the N-alkylation products of phenylaminoacetic acid

iso-amyl ester, in the form of their hydrochlorides.

We claim:

1. As a novel therapeutically useful compound, the isoamylester of alpha - (N' - diethylaminoethyl-N-amino) - phenylacetic acid of the formula

wherein R stands for the isoamyl radical.

2. As a novel therapeutically useful compound the hydrochloride of the isoamylester of alpha - (N' - diethylaminoethyl - N - amino) - phenylacetic acid.

3. A method for producing the isoamylester of alpha - (N' - diethylaminoethyl - N - amino) - phenylacetic acid which comprises reacting alpha

phenylaminoacetic acid isoamyl ester in the absence of solvents with diethylaminoethyl-chloride hydrochloride.

4. A method for producing the isoamylester of alpha - (N' - dimethylaminoethyl - N - amino) - phenylacetic acid which comprises reacting alpha phenylaminoacetic acid isoamylester in the absence of solvents with dimethylaminoethylchloride hydrochloride.
